UNITED STATES PATENT OFFICE.

HARRY C. CLAY, OF DAYTON, OHIO.

STEAM-ENGINE GOVERNOR.

SPECIFICATION forming part of Letters Patent No. 546,728, dated September 24, 1895.

Application filed June 29, 1895. Serial No. 554,416. (No model.)

To all whom it may concern:

Be it known that I, HARRY C. CLAY, a citizen of the United States, residing at Dayton, in the county of Montgomery and State of Ohio, have invented certain new and useful Improvements in Steam-Engine Governors; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

15 My invention relates to improvements in steam-engine governors of the automatic-shaft type. The device has many features in common with swinging eccentric-governors in use; but some features are novel, as will 2c be fully hereinafter described and claimed. The eccentric which gives motion to the engine-valve is suspended within a case fixedly attached to the engine-shaft, and the combination of parts forming the governor increases 25 and diminishes the throw of the valve, and thereby regulates the motion of the engine.

The object of my invention is the construction of an automatic-shaft governor, which will prove effectual and highly sensitive, with 30 a view to greater uniformity in the motion of the engine. The object is accomplished by the mechanism illustrated in the accompanying drawings, in which—

Figure 1 is a back view of the governor, 35 with the arms of the case and portions of the spiral springs cut away to exhibit more clearly the operative parts. Fig. 2 is a transverse sectional view on line α α , Fig. 1.

Like letters designate like parts in the two 40 views.

The cylindrical case C is fixedly keyed to the engine-shaft and forms the support to the several parts of the governor. Within the lugs W W of the case is suspended on the 45 bolt B the principal eccentric A. To the strap V' of this eccentric is attached, in the usual manner, the valve-rod N, which connects said eccentric to the engine-valve, and through which the reciprocating movement is effected. 50 The two parts of the eccentric-strap V V' are united, as usual, by bolts. The two heavy arms G are held on the arms C' of the case by the

bolts H. To the ears on the free ends are attached the links J, which engage the ears of the auxiliary eccentric F by means of the pins 55 T, which are held in place by the set-screw U. There are two pairs of the spiral springs O O. These are hooked onto pins P P on both sides of the heavy arms or weights G, and the other ends are bound to grooved circular nuts, 6c which are engaged by the tension-screws Q, and which have bearings C³ within the rim of the case. These springs counteract the centrifugal force of the heavy arms, and by the screws the adjustment of the tension is made 65 to give the required motion to the engine. The auxiliary eccentric F is fitted over and turns on the hub of the case C concentric to the engine-shaft. The straps of this eccentric comprise the parts K K' K² and are connected by the trunnion L to the principal eccentric.

K is the bearing-plate, its front face being the arc of a circle and bears within the groove of the eccentric F, the back part of which is 75 curved, and central in this part is a semicircular bearing for the connecting-trunnion L. The rear eccentric-strap K' is connected to the forward strap, as usual, and its inner surface corresponds to the outline of said bearing-plate and at its center is provided with a bearing for said trunnion, which is held between said parts. Said trunnion is provided with a plate, by which it is attached to the principal eccentric by the screws M. The 80 two parts of the rear strap are separable, in order that any wear of the auxiliary eccentric or of the trunnion-bearing can be taken up by the bolts and their nuts S, which unite the two principal parts of the strap, thus 85 tightening both bearings by the same adjustment. When it is desirable to give an opposite motion to the engine, the weighted arms are pivoted at C² C², the tension-screws of the spiral springs are attached at C⁴ C⁴, and a reverse motion results. As the weighted arms are moved by the centrifugal force, the auxiliary eccentric is carried partially around on its bearing, which is central to the engine-shaft, and proportionately the principal eccentric is moved forward and backward in 90 line with the valve-rod, and the reciprocating movement of the valve is thus determined. To make the operation as nearly isochronous 95 100

as possible the centrifugal force of the arms must be slightly in excess of the tension of the spiral springs.

Having fully described my invention, what 5 I claim, and desire to secure by Letters Patent, is—

1. In an engine-shaft governor the combination of the case rigidly attached to the engine shaft, the pivotal arm suspended within 10 said case, the principal eccentric held on the free end of said arm, the weighted-arms pivotally suspended from said case, the tension springs uniting said case with said weighted-arms, the auxiliary eccentric, the rear strap 15 comprising two parts with bearings and united by links to said weighted arms, the trunnion held in bearings of said rear strap and uniting the two eccentrics, and the prin-

cipal one having connection with the engine valve, substantially as described.

2. The combination of the auxiliary eccentric provided with the straps K K' the latter provided with a central bearing, the inner bearing plate K, to engage the face of the eccentric, and provided with a like central bearing, the principal eccentric and the trunnion connecting the two, substantially as and for the purpose specified.

In testimony that I claim the foregoing as my own I affix my signature in presence of 30 two witnesses.

HARRY C. CLAY.
